ATTY'S.

UNITED STATES PATENT OFFICE.

THOMAS DODDS, OF THESSALON, ONTARIO, CANADA.

INVALID-BED.

1,276,885.

Specification of Letters Patent. Patented Aug. 27, 1918.

Application filed March 25, 1918. Serial No. 224,598.

To all whom it may concern:

Be it known that I, THOMAS Dodds, a subject of the King of Great Britain, and resident of Thessalon, in the Province of Ontario, Dominion of Canada, have invented certain new and useful Improvements in Invalid-Beds, of which the following is a specification.

This invention relates to improvements in invalid beds, and the objects of the invention are to provide a simple and effective device which may readily be applied to any bed and by which a comfortable support may be provided to hold the occupant of the bed in a raised or sitting position, and it consists essentially of the improved construction, hereinafter described in detail in the accompanying specification and drawings.

20 In the drawings;

Figure 1 is a perspective view of the invention.

Fig. 2 is a detailed end elevation.

In the drawings, like characters of reference indicate corresponding parts in the several figures.

Referring to the drawings, A represents the bed comprising a suitable frame 8 within which the mattress frame C is suitably supported. The rear portion 10 of the mattress frame is hinged to the forward portion, so that it may be elevated as indicated in the drawings and I have in accordance with the present invention provided means 30 to effect this elevating. The means which I have devised comprises racks 11 which are pivoted to the section 10 and which are held by straps 12 in engagement with pinions 13 on a cross shaft 14, journaled in suitable 35 bearings 15 on the frame B and adapted to be turned by suitable cranks 16.

The movable section 10 is adapted to be held in adjusted position by means of the pivoted pawl or dog 17 pivoted to a bracket 40 18 on the frame B and held by a spring 19 in engagement with a ratchet or gear wheel 20. This pawl 17 is adapted to be released from the ratchet wheel 20 by suitable means, the means I have illustrated comprising a

small crank shaft 21, the crank 22 of which 50 is adapted when turned to engage and raise the pawl.

The crank 22 is conveniently provided with a U-shaped bail 23 which extends around the pawl. The crank shaft 21 is 55 journaled in suitable bearings 24 and is adapted to be turned by a crank 25 on the extremity thereof.

It will be seen that the present invention is a very simple but effective construction, 60 and provides a means by which the mattress of a bed may be raised to support the occupant in a sitting or partially reclining position. It is very simple to operate and may with very little expense be applied to any 65 bed.

As many changes could be made in the above construction and many apparently 70 widely different embodiments of my invention within the scope of the claim, constructed without departing from the spirit or scope thereof, it is intended that all matter contained in the accompanying specification and drawings shall be interpreted as 75 illustrative and not in a limiting sense. 75

What I claim as my invention is:

A bed comprising a hinged member, means for raising and lowering said member including a ratchet carrying rotatable shaft, and means for maintaining said shaft 80 in adjusted position comprising a bracket carried by the headboard frame, a pawl supported therefrom engaging said ratchet, a spring also carried by the headboard frame engaging said pawl, bearings depending from the bed frame, a handled shaft journaled therein having a cranked portion adapted to engage and release the pawl 85 from the ratchet, and a U-shaped bail carried by said crank shaft encircling said 90 pawl.

In witness whereof I have hereunto set my hand in the presence of two witnesses.

THOMAS DODDS.
